US00D959203S

(12) **United States Design Patent** (10) **Patent No.:** **US D959,203 S**
Kent et al. (45) **Date of Patent:** **** Aug. 2, 2022**

(54) **BOTTLE**

(71) Applicant: **Revelution Technology, LLC**, Carson, CA (US)
(72) Inventors: **Joshua Kent**, Carson, CA (US); **Christanne Cabal**, Carson, CA (US); **DanAngelo Cabal**, Chesapeake, VA (US); **Rebekah Cabal**, Chesapeake, VA (US)

(73) Assignee: **REVELUTION TECHNOLOGY, LLC**, Carson, CA (US)

(**) Term: **15 Years**

(21) Appl. No.: **29/717,032**

(22) Filed: **Dec. 13, 2019**

(51) LOC (13) Cl. **07-01**
(52) U.S. Cl.
USPC **D7/511**; D7/300.1
